ALFRED GRIEB, OF ELIZABETH, AND NICHOLAUS KNAUS, OF NEWARK, NEW JERSEY,
ASSIGNORS TO THE SINGER MANUFACTURING COMPANY, OF ELIZABETH, NEW JER-
SEY, A CORPORATION OF NEW JERSEY

LUBRICATING SYSTEM FOR SEWING MACHINES

Application filed August 20, 1931. Serial No. 558,228.

This invention relates to sewing machines, more particularly of the type having a bed and a raised cloth-plate between the levels of which is journaled the main-shaft and various other parts of the stitch-forming and feeding mechanisms. The invention has for an object to provide for the thorough and efficient lubrication of the machine to insure long life under high speed operating conditions.

The invention comprises the devices, combinations and arrangements of parts herein-after described and particularly pointed out in the appended claims.

The features of the invention and the advantages attained thereby will be readily understood by those skilled in the art from the following detailed description of a preferred embodiment of the invention illustrated in the accompanying drawings in which Fig. 1 is a front side elevation, partly in section, of the machine. Fig. 2 is a section on the line 2-2, Fig. 1. Fig. 3 is a horizontal section through one of the main-shaft bearings on the line 3-3, Fig. 1. Fig. 4 is a rear side elevation, partly in section, of the machine. Fig. 5 is a transverse vertical section on the line 5-5, Fig. 1. Fig. 6 is a longitudinal vertical section of the feed-rocker supporting shaft shown in Fig. 4. Fig. 7 is a left end elevation of the machine. Fig. 8 is a section on the line 8-8, Fig. 4. Fig. 9 is a section on the line 9-9, Fig. 4. Fig. 10 is a section on the line 10-10, Fig. 1. Fig. 10^a is a perspective view of the bushing for the left end of the shaft shown in Fig. 10. Fig. 10^b is a section on the line 10^b of Fig. 10. Fig. 11 is a vertical section longitudinally of the supporting shaft shown in Fig. 10. Fig. 12 is a section on the line 12-12, Fig. 1. Fig. 13 is a vertical section on the line 13-13, Fig. 7. Fig. 13^a is a plan view of the feed-lift and trimmer-actuating eccentrics. Fig. 14 is a section on the line 14-14, Fig. 5. Fig. 15 is a section on the line 15-15, Fig. 7. Fig. 16 is a perspective view of the lubricator for the feed-actuating eccentric. Fig. 17 is a horizontal section through the ring of the lubricator shown in Fig. 16. Fig. 18 is a horizontal section through the bearing bush-

ing shown in Fig. 13, and Fig. 19 is a side view of the main feed-bar.

The machine comprises a frame including a flat bed casting 1 formed in its under face with an oil-cavity 2 the bottom of which is closed by the oil-tight removable cover-plate 3.

The stitch-forming and feeding mechanisms of the machine, as well as the main-shaft and actuating elements carried thereby, are supported in their usual accessible positions above the bed 1 and exteriorly of the oil-cavity 2 by suitable lugs arising from the bed 1 and preferably cast integral therewith.

The main-shaft 4 is journaled at one end in the bushing 5 received in the main bed-lug 6 upon which the sewing machine bracket-arm or gooseneck 7 is rigidly mounted; said gooseneck terminating in the usual head 8 for the support of the usual needle-bar 9 carrying the needle 10.

The bushing 5 has a longitudinally extending wick-filled channel 11 in the bottom of its bearing surface and has a wick-filled cavity 12 in its outer surface, which cavity is cut through into communication with the channel 11. The lug 6 is drilled out to receive the wick 13 having an anchor knot 14 at its upper end to prevent sagging, which knot 14 is in engagement with the wicking in the cavity 12. The wick 13 conducts oil from the cavity 2 upwardly through the bed 1 and lug 6 to the bearing bushing 5 where it is distributed longitudinally of the portion of the main-shaft within the bushing 5. The spiral groove 14' in the main-shaft carries the oil toward the left or inner end of the bushing 5, Fig. 1, where the escaping oil is caught in the undercut groove 15 of the collar 16 on the main-shaft and is thrown centrifugally through the duct 17 to the ball-crank bearing 18 of the needle-bar reciprocating mechanism.

Oil passes from the bearing 18 upwardly through the hollow pitman 19 to the bearing connection 20 between the pitman 19 and the needle-lever arm 21 which latter is fixed to the rock-shaft 22 journaled in the bearing bushings 23, 23 carried by the gooseneck 7.

Oil is carried from the oil-cup 24 to one of the bushings 23 through the duct 25 and passes to the other bushing through the wick-filled axial aperture 26 in the shaft 22. The rock-shaft 22 has fixed thereto the lever-arm 22^a which is connected by the link 22^b to the needle-bar 9.

The main-shaft 4 is journaled at its other end, Fig. 13, in the bearing bushing 27 carried by the bed-lug 28 and formed with the wick-filled channel 29 and cavity 30 to which the oil is conducted from the main reservoir 2 through the hole 31 drilled in the bed-lug 28; the hole 31 being filled with the wick 31' the upper end of which is formed with the anchor knot 31''.

Cooperating with the needle 10 is the usual threaded looper 32 and overedge implement 33. The looper 32 is mounted on the looper-carrier 34 having a tubular hub 35 journaled on the stationary horizontal shaft 36 fixed in the central lug or upward extension 37 of the bed 1. The shaft 36 has in its under side a wick-filled channel 38 which conducts the oil from the wick-filled supply hole 39 from the main-reservoir 2 to the bearing surfaces between the sleeve 35 and shaft 36.

The sleeve 35 is formed with a boss 40 which is socketed to receive a pin 41 embraced by an actuating sleeve 42 fixed to the bearing pin 43 journaled in the free end of the arm 44 of a bell-crank lever 44, 45, the arm 45 of which carries the overedge implement 33. The boss 40 and pin 41 are formed with connected passageways 46, 47 to conduct lubricant from the bearing pin 36 to the outer surface of the pin 41.

The bell-crank lever 44, 45 has a sleeve-like hub 48, Fig. 10, which is journaled on the stationary shaft 49 fixed at its ends in the lugs 50, 51, rising from the bed 1. The hub 48 has fixed to it a third arm 52 carrying the ball-headed stud 53 which is connected by the link 54 to the ball-crank 55 on the main-shaft 4. The crank 55 is lubricated with the oil which escapes from the left end of the bushing 27, Fig. 13, and is caught in the undercut groove 56 of the crank-hub 57 and conducted through the holes 58, 59 to the bearing surface of the crank 55. Oil from the crank 55 is conducted through the hole 60 in the pitman 54 to the stud 53.

The stationary shaft 49 is provided with wick-filled channels 61 in capillary connection with the wick-filled holes 62, 63 in the lugs 50, 51 leading upwardly from the main oil-cavity 2. The shaft 49 is fixed at its reduced end in a bushing 64 having its under wall slabbed off at 65 to clear the wick-knot 62'' which touches the wicking in the channels 61. The bushing 64 and shaft 49 may be inserted and removed after the knotted wick 62 has been placed in its hole in the

bed 1. Oil is conducted from the stationary shaft 49 through the hole 66 in the bell-crank arm 44, Fig. 15, to the bearing pin 43.

The feeding mechanism comprises a main feed-dog 67 and auxiliary feed-dog 68 carried respectively, by the main feed-bar 69 and auxiliary feed-bar 70; the latter bar being fulcrumed at 71 on the main feed-bar. The main feed-bar 69 has fixed to its rear end the cross-pin 72 which is journaled in the up-standing arms 73, 73, Fig. 4, of the feed-rocker 74 journaled on the stationary feed-rocker-supporting shaft 75 which is fixed in the bushings 76 in the bed-lugs 77. The feed-rocker 74 has fixed to it a crank-arm 78 which is connected by the pitman 79 to the adjustable feed-eccentric 80 slidably mounted as usual in a transverse groove 81 in the feed-eccentric carrier 82 fixed to the main-shaft 4. The eccentricity of the eccentric 80, and thus the length of the feed-stroke of the main feed-dog, is adjusted by turning the adjusting screw 83, Fig. 13, the head of which engages a slot 84 in the adjacent face of the feed-eccentric 80.

The feed-rocker-supporting shaft 75 has the wick-filled channels 85 which absorb oil from the knots 86 at the upper ends of the wicks 87 disposed in holes in the bed-lugs 77 and leading upwardly through the bed 1 from the main oil-cavity 2 in the under face of the bed. The wick-filled channels 85 distribute the oil along the shaft 75 from which a certain amount of oil is picked up and centrifugally thrown through the ducts 88 in the rocker-arms 73 to the bearings for the pin 72.

The main feed-bar is supported by the pin 89, Figs. 5, 13 and 19, of the short vertical pitman 90 embracing the feed-lift eccentric 91 on the main-shaft 4. The feed-lift eccentric 91 is formed integral with the trimmer-actuating eccentric 92 which is connected by the hollow pitman 93 to the trimmer-lever 94 fulcrumed at 95 on the frame and carrying the usual trimmer-blade 96 at its forward end. The main-shaft 4 is formed within the eccentrics 91 and 92 with a wick-filled channel 97 which conducts oil from the wicking 29 to the shaft-groove 98 and through the duct 99 to the bearing surface of the trimmer-actuating eccentric 92 from which oil is conducted through the duct 101 to the pin 102 which connects the pitman 93 to the trimmer-lever 94.

Oil also passes from the channel 97 outwardly across the left end face of the feed-lift eccentric 91 Fig. 13, to the feed-lift-eccentric bearing along which it is distributed by the spiral slit 100 the trailing end of which is cut through to conduct excess lubricant to the trimmer-actuating eccentric and assist in lubricating the latter and the pin 102 above.

There is freely mounted on the main-shaft 4, between the trimmer-actuating eccentric

92 and the feed-eccentric-carrier 82, a collar 103 formed in that face adjacent the feed-eccentric-carrier 82 with a circular wick-filled channel 104 which is continuous with the 5 wick-filled duct 105 leading downwardly from the collar 103 and into the main oil-cavity 2. The channel 104 is overhung by the under-cut groove 106 in the adjacent face of the eccentric carrier 82. Leading through 10 the eccentric-carrier 82 from the under-cut groove 106 is the duct 107 which terminates within the internal groove 108 in the feed-eccentric 15 80. The duct 107 does not interfere with the adjustment of the eccentric 80 and conducts lubricant from the collar 103 to the latter; the lubricant passing through the hole 108' to the eccentric bearing surface.

Oil is supplied to the main cavity 2 through the main oil-cup 109 and is conducted by 20 the several wicks, as described, to the various bearings.

The removable plate 3 has fixed thereto the lug 110 having therein the blind screw-threaded hole 111 for reception of the fastening screw 112 by means of which the entire machine is firmly secured in operative position upon the felt pads 113 resting upon lugs 114 in the cast-iron pan 115 fixed to the table-top 116. Surplus or spent oil may be drained 30 from the pan 115 from time to time through the pipe and drain-cock 117.

The usual throat-plate 118, over which the work passes, is supported above the main-shaft 4, by the bed-lugs 28 and 51', the latter 35 being an upward extension of the lug 51. The usual cloth-plate, not shown, is supported at the level of the throat-plate 118.

Having thus set forth the nature of the invention, what we claim herein is:—

40 1. A sewing machine comprising a frame-casting including a flat bed recessed in its under face to form an oil-cavity, stitch-forming and feeding mechanisms disposed above and carried by said bed externally of said oil-cavity, wick-filled conduits leading upwardly from said oil-cavity through said bed to working bearings of said mechanisms, and a removable plate secured to said bed and closing the bottom of said oil-cavity.

45 2. A sewing machine comprising a frame-casting including a flat bed recessed in its under face to form an oil-cavity, supporting lugs rising from said bed, stitch-forming and feeding mechanisms supported above and externally of said bed by said supporting lugs, a main-shaft journaled above and externally of said bed, a system of wick-filled conduits leading upwardly from said oil-cavity through said bed-casting and supporting lugs

50 to working bearings of the main-shaft and stitch-forming and feeding mechanisms, and a removable plate closing the bottom of said oil-cavity.

55 3. A sewing-machine comprising a frame-casting including a flat bed recessed in its

under face to form an oil-cavity, stitch-forming and feeding mechanisms disposed above and carried by said bed externally of said oil-cavity, wick-filled conduits leading upwardly from said oil-cavity through said bed to 70 working bearings of said mechanisms, and a removable plate secured to said bed and closing the bottom of said oil-cavity, said plate being formed with a screw-threaded aperture for reception of a fastening screw, whereby 75 the entire machine may be fixed to a supporting table-top.

4. A sewing machine comprising a frame-casting including a flat bed recessed in its under face to form an oil-cavity, said bed having supporting lugs rising therefrom, bearing-elements inserted in said supporting lugs above said bed and externally of said oil-cavity, said bearing-elements having wick-filled channels in their bearing surfaces, said bed and bed-lugs being drilled out to form 80 conduits leading upwardly from said oil-cavity through said bed to said channeled bearing-elements, and wicks disposed in said conduits and in capillary working relation with 85 said wick-filled channels.

5. A sewing machine having a flat bed formed with an oil-cavity, a main-shaft journaled above the upper side of said bed, feeding mechanism including a feed-dog and an adjustable feed-actuating eccentric on said main-shaft, and means for conducting lubricant from said oil-cavity upwardly through said bed to said feed-actuating eccentric.

6. A sewing machine having a rotary shaft, a stationary ring-member surrounding said shaft and having a recess in one face thereof, an eccentric support fixed to said shaft adjacent said ring-member and having an under-cut groove overhanging said recess, said support also having a conduit leading from said groove through and beyond said support lengthwise of said shaft, an eccentric adjustably mounted on said support and formed with an internal recess overhanging the delivery end of said conduit, and means for conducting lubricant to the recess in said stationary ring-member.

7. A sewing machine having a flat bed formed with an oil-cavity, a main-shaft journaled in spaced bearings above said bed, an eccentric carried by said shaft between and spaced from said bearings, said eccentric having an under-cut recess, and means for conducting lubricant from said oil-cavity to said recess, said means including a stationary ring-shaped member on said main-shaft adjacent said eccentric and having a conduit leading to said oil-cavity.

8. A sewing machine having a flat bed formed with an oil-cavity, a reciprocating needle, a complementary threaded looper and an overedge implement journaled on said bed above and externally of said oil-cavity, said bed having wick-filled passageways leading 125

from said cavity upwardly to the bearings for said looper and overedge implement, a hollow pin rigid with said looper and receiving oil from the looper-bearing, a sleeve embracing said pin, an actuating connection between said overedge implement and said sleeve for driving said looper, and means for driving said overedge implement.

9. A sewing machine having a flat bed formed with an oil-cavity, a lug rising from said bed, a main-shaft bearing bushing in said lug, a main-shaft journaled in said bushing, a looper-actuating crank on said main-shaft adjacent one end of said bushing, feed-lift and trimmer-actuating eccentrics on said main-shaft adjacent the other end of said bushing, means for conducting lubricant from said cavity through said lug to said bearing bushing, and means for conducting lubricant from the opposite ends of said bushing to said looper-actuating crank and to said feed-lift and trimmer-actuating eccentrics.

10. In a sewing machine, a flat bed having an oil-cavity, a lug rising from said bed, a stationary shaft removably fixed in said lug, said shaft having a wick-filled channel extending lengthwise thereof, said lug having a wick-filled aperture leading upwardly from said oil-cavity into capillary connection with said channel, and a working element journaled on said stationary shaft.

11. In a sewing machine, a flat bed formed with an oil-cavity, spaced lugs rising from said bed, a stationary shaft mounted at its opposite ends in said spaced lugs, said shaft having a wick-filled channel extending longitudinally thereof, said lugs having wick-filled apertures leading upwardly from said oil-cavity and in capillary connection with said channel, and a rocking sleeve-member journaled on said stationary shaft.

12. In a sewing machine, a frame including a flat bed formed with an oil-cavity and with a plurality of lugs rising therefrom, stitch-forming and feeding mechanisms journaled in said frame and including parts journaled in said lugs, removable bearing elements for said parts, having wick-filled channels, said lugs having holes therein leading upwardly from said oil-cavity, and wicks in said holes in capillary connection with said wick-filled channels.

13. The structure set forth in claim 12 with means for anchoring the wicks in the holes in the lugs.

14. The structure set forth in claim 12 in which the wicks in the holes in the lugs are formed with anchor-knots at their upper ends.

15. A sewing machine having a frame including a flat bed casting having bearing lugs rising therefrom and formed with a main oil-cavity, a throat-plate supported above said bed by certain of said lugs, a main-shaft jour-

naled above said bed, exteriorly of said oil-cavity and below said throat-plate, stitch-forming and feeding mechanisms incorporated in said frame and disposed exteriorly of and above said oil-cavity, said mechanisms including working parts having bearings supported exteriorly of said oil-cavity by said bearing lugs, said bearing lugs having wick-filled apertures leading upwardly from said oil-cavity to said bearings.

In testimony whereof we have signed our names to this specification.

ALFRED GRIEB.
NICHOLAUS KNAUS.
